Elias Ingraham, of Bristol, Conn.
Letters Patent No 1662, dated Sept. 30, 1862.

The schedule referred to in these Letters Patent and making part of the same.

To all whom it may concern:

Be it known that I, Elias Ingraham, of Bristol, County of Hartford and State of Connecticut, have invented or produced a new and original design for a clock base; and I do hereby declare that the following is a full and exact description of the same, referring to the photographic views, in which the same letters indicate like parts.

In the accompanying illustrations.

A, is the case proper. B, is the front of the case, a, are plane rounded portions of the side of the case, surrounded by a plain rounded upper portion c, of the sides and top of the case proper. d and e, are round plain beaded portions of the sash, or front of the case. f, is the time dial. the whole combined to produce a plain and rich design for a clock case.

What I claim and desire to secure by Letters Patent, is the design for a clock case substantially as illustrated and described.
